UNITED STATES PATENT OFFICE.

EDWARD AUGUST HEYER, OF NEW YORK, N. Y.

WALL CONSTRUCTION.

Application filed July 9, 1925. Serial No. 42,535.

To all whom it may concern:

Be it known that I, EDWARD A. HEYER, a citizen of the United States, and a resident of the city of New York, borough of Manhattan, in the county and State of New York, have invented a new and Improved Wall Construction, of which the following is a full, clear, and exact description.

This invention relates to wall construction and method of making the same, and more specifically to an improved enameled sheet metal construction forming a portion of the wall and serving as a substitute for tile wainscoting and the like so that the surface or wall will be entirely waterproof and be constructed at relatively low cost.

A further object is to provide an improved wall construction embodying novel steps in the method of construction, all of which will be more fully hereinafter described and pointed out in the claims.

In the accompanying drawings—

Figure 1 is a view in elevation showing the wall in the course of construction, parts being broken away to illustrate other parts;

Figure 2 is a view in longitudinal section on the line 2—2 of Figure 1;

Figure 3 is a view in front elevation showing one section of the wall completed and the other portion of the wall partially completed;

Figure 4 is a fragmentary view in section on the line 4—4 of Figure 3;

Figure 5 is a view similar to Figure 4, taken on the line 5—5 of Figure 3.

In constructing my improved wall I employ ordinary studs 1 with lathes 2 nailed thereon. To the lathes 2 I nail horizontal strips 3 and vertical strips 4 of wood or analogous material. These strips 3 and 4 are of a thickness or depth equal to the thickness of plaster 5 which is then placed on the wall and is flush with the strips 3 and 4.

These strips 3 and 4 I shall hereinafter refer to as supporting strips in order to distinguish them from the other strips which are used.

If my improvements are to be secured to a brick or stone wall, the supporting strips 3 and 4 may be affixed thereto in any approved manner.

On these supporting strips 3 and 4 I secure metal plates 6 having their vertical adjacent edges slightly spaced apart and secured to the vertical strips 4 with the up-

per and lower ends of the plates 6 secured to the supporting strips 3. These metal plates are preferably enameled and may be white or any other color, and may be ornamented in any desired manner.

Over the adjacent vertical edges of the plates 6 I secure strips 7, which are preferably of rubber or other analogous material so as to render the joints watertight. These strips 7 at their upper and lower edges are preferably of general V-shape, as shown at 8, and fit in correspondingly shaped recesses 9 in horizontal strips 10, which cover the upper and lower edges, respectively, of plates 6.

Over these rubber strips 7 I locate vertical covering strips 11, which are preferably of metal and which are secured in place, preferably, by screws or other attaching devices 12, which are projected through the metal strips 11, through the rubber strips 7, between the edges of plates 6 and into the supporting strips 4.

Strips 13, similar to the strips 11, cover the horizontal strips 9 but are appreciably shorter, and coupling plates 14 of metal enclose the adjacent ends of the strips 11 and 13 and form an ornamental finish to the design.

These plates and metal strips may be colored and ornamented, enameled and otherwise constructed so as to give the desired appearance, but it is to be understood that the purpose of the wall is to give an imitation tile, or what may correspond to a tile or waterproof wainscoting, for any use to which such a construction may be put.

The metal strips 11 not only cover the rubber strips 7 but they exert sufficient pressure thereon so as to render the juncture of the parts entirely watertight and also prevent the passage of water bugs and other insects through the wall.

Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. The herein described wall construction, consisting in supporting strips located at an angle to each other, metal plates secured to said strips and spaced apart at

their edges, strips of flexible material secured over the meeting edges of the plates and at the ends of the plates, and metal strips covering the flexible strips and secured to the plates thereover.

2. A wall construction, including horizontal and vertical supporting strips, plates secured at their ends and side edges to the respective supporting strips, rubber strips covering all of the meeting edges of all of the plates and having tongue and recess juncture between the vertical and horizontal rubber strips, metal strips covering the vertical strips and the horizontal strips, and metal coupling members at the juncture of the horizontal and the vertical metal strips, and securing devices projected through the metal strips and the rubber strips and into the supporting strips.

10 3. A wall construction, including horizontal and vertical supporting strips, plates secured at their ends and side edges to the respective supporting strips, rubber strips covering all of the meeting edges of all of the plates and having tongue and recess juncture between the vertical and horizontal rubber strips, and metal strips enclosing the rubber strips.

15 horizontal and vertical supporting strips, plates secured at their ends and side edges to the respective supporting strips, rubber strips covering all of the meeting edges of all of the plates and having tongue and recess juncture between the vertical and horizontal rubber strips, metal strips covering the vertical strips and the horizontal strips, and metal coupling members at the juncture of the horizontal and the vertical metal strips, and securing devices projected through the metal strips and the rubber strips and into the supporting strips.

EDWARD AUGUST HEYER.
